ABSTRACT OF THE DISCLOSURE

The invention comprises an envelope adapted to hold a sheet of foamed plastic. One side of the envelope is perforated. When the mat is placed adjacent a door opening and the perforated side is walked upon, dirt from the shoes passes through the perforations onto the foamed plastic where it is collected and held until the foamed plastic is removed from the envelope, cleaned and then replaced in the envelope. The theory is that dirt particles receive an electrostatic contact charge when the foot of the person steps upon the perforated surface of the envelope which charge draws the dirt and dust through the perforations to hold the same within the envelope upon the foamed plastic sheet.

An object of the invention is to provide an inexpensive mat adapted to collect dirt and dust and to hold the dirt and dust trapped within an envelope until its removal therefrom.

The device of the invention is particularly useful at doors such as front or rear doors, so that a person entering through the door will deposit dirt or dust from the feet on the mat which dirt and dust passes within the envelope of the mat and is held therein by electrostatic attraction. The mat may be used in automobiles, bathrooms and other locations.

A further object is a mat which is inexpensive in cost of manufacture, useful, has no parts subject to disorder and which is a help in preventing excess dust and dirt from being carried within a dwelling or other structure.

In the drawing:

FIG. 1 is a fragmentary perspective view of a door and its opening with the mat of the invention in position for contact with the shoes of the person entering through the door opening;

FIG. 2 is an enlarged plan view of the top surface of the mat envelope;

FIG. 3 is a fragmentary bottom plan of the mat envelope with a filler within the same;

FIG. 4 is a sectional view, on an enlarged scale, taken on the line 4—4 of FIG. 2; and

FIG. 5 is a transverse sectional view, on an enlarged scale, taken on the line 5—5 of FIG. 2;

FIG. 6 is a view of the filler removed from the mat envelope.

Referring to the drawing and specifically FIGS. 2 to 6 inclusive, the mat of the invention includes an envelope 1 having a top member 2 and a bottom member 3, the sides and one end of the said members being heat sealed adjacent the longitudinal and lateral edges as shown at 4, 5, and 6, the envelope being provided with a transverse flap 7 heat sealed to one end of the top member as shown at 8, the flap adapted to overlie in part the bottom member 3 as shown in FIG. 4. Thus the envelope is preferably formed from a plastic material such as polyvinyl chloride, by way of example. The top member is provided throughout its length and breadth with transverse perforations 9

2

leading from the top surface to the interior of the envelope. Within the envelope is a removable thin filler 10 which has dimensions to fit closely within the interior of the envelope. This thin filler is preferably formed of foamed polyurethane plastic.

The operation, uses and advantages of the invention are as follows.

The mat, including the envelope and the thin filler within the same may be placed in any desired location such as the interior of a dwelling or other building structure for contact by the feet when the door is opened for admittance of a person, as shown in FIG. 1. The mat works particularly well on a wool rug from which it readily gets static electrical charges. The present mat is auxiliary to any mat that may be exterior of the door and which exterior mat does not collect all of the dirt and dust from the feet so that when the mat 1 is contacted any remaining dirt on the feet will contact the top member and the dirt will pass through the perforations 9 by electrostatic attraction within the envelope and deposit upon the top surface of the thin filler 10. The usefulness of the mat aids materially in preventing additional dirt and dust from entering the house or dwelling for contact with carpets and floors.

25 The device is believed to operate on an electrostatic principle and may be electromagnetic as well, although it has been found from experience that contact charges are made upon the top surface of the mat by the foot which is sufficient to charge the dirt particles so that the particles are deposited upon the charged filler. After use of the mat, the mat may be cleaned by opening the flap 7 to expose the interior of the envelope and the removal of the filler. The filler may then be washed, dried and replaced within the envelope.

30 It is obvious that other means may be utilized for securing the edges of the top and bottom members of the envelope together although in the case of plastic it has been found that heat sealing is simple and economical.

I claim:

1. A mat, comprising: a flexible envelope having a top member and a bottom member both formed from polyvinyl chloride material, and a removable foam plastic filler within the envelope, said top member provided with a plurality of transverse perforations throughout its length and breadth.
2. The device as set forth in claim 1, characterized in that: the bottom member is imperforate.
3. The device as set forth in claim 1, characterized in that the foamed plastic filler is formed of polyurethane.
